United States Patent Office

Des. 180,148
Patented Apr. 23, 1957

180,148

WARDROBE HANGER

Beverly Jo Kellogg, Altadena, Calif.

Application January 24, 1955, Serial No. 34,169

Term of patent 7 years

(Cl. D33—8)

Figure 1 is an end elevation of the wardrobe hanger.
Figure 2 is a side elevation thereof.

Figure 3 is a perspective of the wardrobe hanger.

I claim:

The ornamental design for a wardrobe hanger, as shown.

References Cited in the file of this patent

UNITED STATES PATENTS

2,513,759 Tarallo ----- July 4, 1950

FOREIGN PATENTS

366,128 France ----- Sept. 27, 1906

OTHER REFERENCES

Lansburgh's Washington, D. C., 1954 Christmas Catalog, page 66, Item 66 B.